Primary Examiner — Philip S Hyder*Assistant Examiner* — Roselynne Cody(74) *Attorney, Agent, or Firm* — Greenberg Traurig, LLP(57) **CLAIM**

What is claimed is the ornamental design for a bit, as shown and described.

DESCRIPTION

FIG. 1 is a left side elevational view of a bit showing my new design, the right side elevational view being the same;

FIG. 2 is a front side elevational view thereof, the back side elevational view being the same;

FIG. 3 is a top plan view thereof;

FIG. 4 is a bottom plan view thereof; and,

FIG. 5 is a perspective view thereof.

Any elements shown in dotted and/or dashed lines are provided for illustrative purposes only and form no part of the design claimed. Any surface shading is used solely to show the character or contour of the surfaces represented.
